Primary Examiner — Philip S Hyder*Assistant Examiner* — Roselynne Cody(74) *Attorney, Agent, or Firm* — Altis Law Group, Inc.(57) **CLAIM**

The ornamental design for a screwdriver, as shown and described.

DESCRIPTION

FIG. 1 is a perspective view of one embodiment of a screwdriver showing my design;

FIG. 2 is a front elevational view thereof;

FIG. 3 is a rear elevational view thereof;

FIG. 4 is a left side, elevational view thereof;

FIG. 5 is a right side, elevational view thereof;

FIG. 6 is a top plan view thereof; and,

FIG. 7 is a bottom plan view thereof.

The broken lines in the drawings illustrate features of the screwdriver that form no part of the claim.
